UNITED STATES PATENT OFFICE.

WILLIAM McFADDEN, OF DAVIS, WEST VIRGINIA.

TELEPHONE AND TELEGRAPH POLE.

1,189,596.

Specification of Letters Patent.

Patented July 4, 1916.

Application filed October 22, 1913. Serial No. 796,638.

To all whom it may concern:

Be it known that I, WILLIAM McFADDEN, a citizen of the United States, residing at Davis, in the county of Tucker and State of West Virginia, have invented certain new and useful Improvements in Telephone and Telegraph Poles, of which the following is a specification.

This invention relates to improvements in 10 telegraph and telephone poles.

The invention has for its object to provide for readily stringing the wire and making 15 repairs on a telephone or telegraph line or system or gaining ready access to the cross-arms and their equipment.

A further object is to carry out these ends in a simple, expeditious, and effective manner.

The invention consists of certain instrumentalities and features of construction substantially as hereinafter fully disclosed and defined by the appended claim.

In the accompanying drawings is illustrated the preferred embodiment of my invention wherein it will be understood that various changes and modifications may be made as to the detailed construction and arrangement of parts without departing from the spirit of the invention and in which drawing:

Figure 1 is an elevational view of my invention. Fig. 2 is a sectional elevation taken on the line $x-x$ of Fig. 1. Fig. 3 is a fragmental partly plan and partly sectional view the section being taken on the line $y-y$ of Fig. 1. Fig. 4 is a detail perspective view of an anchoring foot-member used in connection with each leg of the tripod-form of pole, which foot-member or anchor has an attaching stud extending into the hollow or tubular leg of the pole or tripod.

In carrying out my invention, I constitute a pole, designated generally as 1, in tripod-outline, of three separate upright hollow or tubular members 2, 3, 4, the member 4 being equipped with or having passed through it suitably spaced-apart rungs or cross-pieces 5 projecting laterally from each side thereof, thus forming a ladder for the convenient or ready ascent of the same by the lineman in stringing the wires up on the cross-arms, or

rather the insulators thereon, or making repairs thereto. The uprights or members terminate in upper end right-lined or straight flat-portions 6 which are suitably bolted or secured together, as at 7, the same assuming a T shaped outline as seen in Fig. 3; to the head of the T thereof is suitably bolted, as at 8, the cross-arm 9 bearing the usual insulators 10, said cross-arms being 60 suitably braced from the pole by means of bars or strips of metal 11, bolted thereto or otherwise, as usual. The base, or lower, ends of the tripod or pole members are suitably planted or anchored in the ground, a 65 suitable distance below the surface, said lower or base ends having applied thereto cast-metal anchoring plates as at 12, the same forming feet therefor, a stud or projection 13 extending diagonally upwardly 70 therefrom into the hollow or interior of the legs of the tripod or pole as seen in Fig. 2, the anchoring member with its stud 13, being more fully shown in Fig. 4.

This device it is apparent, is characteristic 75 for its simplicity and convenience to the lineman in the particulars as above recited as well as providing a substantial pole or support and which is readily erected and with the minimum labor and trouble. 80

Having thus fully described my invention, what I claim and desire to secure by Letters Patent is:—

A device of the type described including a tripod-like arrangement of uprights, with 85 upper end right-lined flat-portions bolted or secured together for the attachment thereto of the cross-arms, said uprights each being hollow or tubular, the upper portions thereof being mashed or pressed together so as to 90 produce said flat-portions, said flat-portions being, when bolted together, T-shaped in horizontal section, leaving one side thereof flat for the purpose of providing a smooth surface contacting said cross-arms. 95

In testimony whereof I affix my signature in presence of two witnesses.

WILLIAM McFADDEN.

Witnesses:

H. A. MEYER,
JEFFERSON T. SMITH.
